STORM WINDOW FASTENER

Joseph L. Quinn, St. Paul Park, Minn.

Application February 27, 1943, Serial No. 477,430

15 Claims. (Cl. 292—263)

My invention relates to an improvement in storm window fastener, wherein it is desired to provide a fastener for pivoted windows, such as storm windows and the like.

Various types of window fasteners have previously been constructed and such devices are in common use. It is the object of the present invention to provide a fastener of the same general type as has been previously constructed, but so devised that the fastener is noiseless in operation and will not rattle when in use.

A feature of the present invention lies in the provision of elongated leaf springs which are connected to the pivoted arms forming the window fastener. These springs are so arranged at the pivot points that the pivots are at all times under spring tension. As a result the fastener can not rattle or come loose at the pivot points.

A feature of the preferred form of my invention lies in the provision of two angularly shaped elements which are pivotally connected together at one end. These angularly shaped elements are so arranged that they provide a locking means for locking the arms in parallel relationship when it is so desired. The flanges are also so arranged that they abut when the arms are swung into longitudinal alignment, thereby limiting the pivotal movement of the arms.

A feature of the preferred form of my invention lies in the provision of elongated spring leaves which extend substantially the length of the pivoted arms. With such a construction the spring leaves may serve not only to maintain the pivotal connection between the two arms under spring tension, but also these springs serve to hold the pivotal connection between the respective arms and the window and window frame under spring tension.

A further feature of the present invention lies in the manner in which one of the spring arms may be detached from its cooperable bracket mounted on the window or the window frame. With such a construction the fastener may be detached from either the window or the window frame to permit the window to be removed from its frame.

These and other objects and novel features of my invention will be more clearly and fully set forth in the following specification and claims.

In the drawing forming a part of my specification:

Figure 1 is a side elevational view of my bracket showing the construction thereof.

Figure 2 is a plan view of my bracket in extended form.

Figure 3 is a perspective view of one of the spring leaves used in conjunction with my fastener.

Figure 4 is a perspective view of one of the arms forming my fastener.

Figure 5 is an exploded view of the pivotal connection between the two arms forming my fastener.

Figure 6 is an enlarged view of the detachable 10 end of one of the arms detached from its bracket.

Figure 7 is a perspective view of the bracket from which the arm end shown in Figure 6 has been detached.

The window fastener A is designed to connect 15 a pivotally hung window such as B to a window frame such as C. The window B is usually pivoted on a horizontal axis at the top of the window and the window may swing outwardly at its lower end an amount regulated by the fastener A. Obviously the fastener A could similarly be used on windows or the like supported on a vertical axis.

The fastener A includes a pair of fastener arms 10 and 11 which are pivotally connected by any suitable pivot means such as the rivet 12. The 25 pivotal connection between the two arms 10 and 11 is best illustrated in Figure 5 of the drawing, which will be later described.

The arm 10 includes an elongated flat strip 13 having rounded ends 14 and 15. Apertures 16 and 17 are provided in the ends 14 and 15 respectively. A flange 19 extends along one edge of the strip 13 at substantially right angles thereto, best illustrated in Figures 1 and 2 of the drawing.

35 The arm 11 is similar in form to the arm 10 comprising a flat strip 20 having rounded ends 21 and 22. Apertures 23 and 24 respectively are provided in the ends of the strip 20. A flange 25 extends longitudinally throughout the length 40 of the straight portion of the strip edge 20, as best illustrated in Figures 1, 2, and 4 of the drawing.

45 Leaf springs are provided extending longitudinally of the arms 10 and 11. A leaf spring 26 extends along the arm 10 adjacent the strip 13. When not fastened in place this leaf spring is bowed in such a manner that the center of the spring would contact the strip 13 while the ends thereof would be spaced from the ends of the strip 13. However, when the fastener is assembled the spring 26 extends substantially parallel to the strip 13.

50 As illustrated in Figures 2, 3, and 6 of the drawing, a spring leaf 27 is provided to extend along the arm 11. The spring 27 is bowed as il-

Illustrated so as to normally touch the strip 20 near the center thereof and to be spaced from this strip at the ends of the spring. However, as illustrated in Figure 2 of the drawing one end of the spring 27 is secured closely adjacent the end 21 of the strip 11 while the other end thereof is normally spaced slightly from the end 22 of the strip 20 for a purpose which will later be described in detail.

With reference to Figure 5 of the drawing the connection between the various elements forming the knee joint or pivot 12 will now be described. The pivot 12 is preferably in the form of a rivet having a shank 29 and a head 30. The shank 29 extends through a washer 31, through the aperture 23 in the arm 11, through an aperture 32 in the spring 27, through the washers 33 and 34, through the aperture 35 in the spring leaf 26, through the aperture 17 in the arm 10, and through a rectangular aperture 36 in the washer 37. The end of the shank 29 of the rivet 12 is then riveted over, deforming the end of the shank so that the rivet turns with the washer 37. This construction is designed to prevent the riveted end of the shank 29 from rotating relative to the washer 37, thereby weakening this relatively weaker connection.

A stile plate 39 is designed for attachment by screws 40 or other suitable means to the window frame C. This stile plate 39 is preferably formed as illustrated in Figures 1 and 2 of the drawing, including aligned ends 41 and an off-set central portion 42. A rivet 43 has its head 44 between this off-set portion 42 of the stile plate and the window frame C and the shank of the rivet 43 extends through a washer 45, through the off-set stile plate portion 42, a washer 46, the aperture 16 in the arm 10, and a rectangular aperture 47 in the spring leaf 26. The end of the rivet shank is deformed so that the rivet will be held from rotation relative to the spring leaf 26 and consequently relative to the arm 10. The shape of the spring leaf is such as to urge the strip 13 of the arm 10 against the washer 46 and simultaneously to urge the washer 45 against the underside of the off-set portion 42 of the stile plate 39, therefore a tight friction joint is maintained between the stile plate 39 and the bracket arm 10.

The spring arms 26 and 27 likewise provide continuous friction at the knee joint or pivot 12. The spring leaves 26 and 27 tend to urge the arms 10 and 11 against the washers 37 and 31 respectively. At the same time the washers 33 and 34 are being held between the springs 26 and 27 under spring tension. To increase the friction effect the washers 31, 33, and 34 are provided with a rim portion which is thicker than the remainder of the washer to insure contact at the rim of the various washers.

The removable connection between the arm 11 and the bracket 49 will be best understood from an examination of Figures 2, 6, and 7 of the drawing. The spring leaf 27 is provided with a rectangular aperture 50 therethrough designed to accommodate the end of a rivet 51. The rivet 51 is provided with a head 52 and a shank 53. The end of the shank 53 is deformed so that no rotation can take place between the spring leaf 27 and the rivet 51. The spring tension of the spring leaf 27 normally draws the head 52 of the rivet 51 against the strip 20 of the arm 11. However, the spring leaf 27 may be flexed toward the strip 20 so that the head 52 may be engaged in a suitable receiving socket in the bracket 49.

The bracket 49 is provided with a base 54 designed for attachment to the window B by screws 55 or other suitable means. A right angular flange 56 extends upwardly from the base 54 designed to extend at right angles to the base. A circular area 57 of this flange 56 is recessed or off-set from the surface of the flange 56 and this circular area 57 is of just the proper size to receive the head 52 of the rivet 51. A slot 59 extending inwardly from the edge of the flange 56 to the center of the circular area 57 is designed to receive the shank 53 of the rivet 51 to permit the head 52 thereof to engage the recessed area 57.

As best illustrated in Figure 2 of the drawing, the spring leaf 27 may be flexed toward the strip 20 of the arm 11 until the head 52 of the rivet 51 is in spaced relation to the strip 20. The shank 53 may then be inserted into the slot 59 so that the head 52 of the rivet is engaged in the circular area 57 in the flange 56. The spring 27 is then released and the head 52 is pulled into the recess 57.

The tension of the springs 26 and 27 may be varied to suit various conditions, but ordinarily this tension is so great that the spring 27 can not be urged toward the strip 20 with the fingers. The fastener is usually attached and detached by springing the spring 27 toward the arm 20 with the aid of pliers, the head 52 being readily removable from the socket 57 in such a condition.

In the drawing the slot 59 is shown extending at substantially right angles from the base plate 54 of the bracket 49. Obviously this slot 59 could enter the socket 57 from another direction, it being possible for this slot to extend substantially parallel to the base 54 if it is so desired. I have found that the spring tension of the spring 27 is sufficient to hold the rivet head 52 in its socket. However, if the tension of the spring 27 is decreased somewhat it may be desirable to lock the slot 59 in a somewhat different manner and so as to enter the circular area 57 from a somewhat different angle from that illustrated.

The flanges 19 and 25 on the arms 10 and 11 respectively, serve a double purpose. In the first place these flanges act to stiffen the strips 13 and 20 which would otherwise bend because of the strength of the leaf springs 26 and 27. In the second place these flanges form a means of locking the window B in closed position. When the window B is closed in its frame C the pivot 51 is coaxial with the pivot 43. By swinging the arms 10 and 11 in unison about their respective pivots until the arms extend vertically upwardly from the pivots 43 and 51, the window will be locked from outward movement by the flanges.

Furthermore the flanges 19 and 25 act to limit relative pivotal movement between the arms 10 and 11. As shown in Figure 1 of the drawing, ends 60 and 61 of the flanges 19 and 25 respectively are positioned so as to abut when the arms 10 and 11 are aligned, thereby preventing the two arms from swinging past aligned position.

In accordance with the patent statutes, I have described the principles of construction and operation of my window fastener, and while I have endeavored to set forth the best embodiment thereof, I desire to have it understood that obvious changes may be made within the scope of the following claims without departing from the spirit of my invention.

I claim:

1. A sash fastener comprising a pair of jointed

arms, a mounting pivoted to one of said arms, a leaf spring secured to the other of said arms to extend longitudinally thereof, a pivot secured to said leaf spring for movement therewith, and a bracket detachably secured to said pivot.

2. A sash fastener comprising a pair of jointed arms, a mounting pivoted to one of said arms, a leaf spring secured to the other of said arms to extend longitudinally thereof, a headed pivot secured to said leaf spring for movement therewith, and a socketed bracket detachably engageable with said headed pivot.

3. A sash fastener comprising a pair of jointed arms, a mounting pivoted to one of said arms, a leaf spring secured to the other of said arms to extend longitudinally thereof, a pivot element secured to said leaf spring for movement therewith and extending through a portion of said other arm, and a bracket detachably engageable with said pivot element.

4. A sash fastener comprising a pair of jointed arms, a mounting pivoted to one of said arms, a leaf spring secured to the other of said arms to extend longitudinally thereof, a rivet secured at one end to said leaf spring for movement therewith, having a head at its other end, and being supported by said other arm intermediate its ends, said spring urging said head against said other arm, and a bracket detachably engageable with the headed end of said pivot.

5. A sash fastener comprising a pair of jointed arms, a mounting pivoted to one of said arms, a leaf spring secured to the other of said arms, a pivot secured at one end to said leaf spring for movement therewith, having a headed other end and being supported by said other arm intermediate its ends, said spring urging said headed end toward said arm, a bracket detachably engageable with said headed end, said bracket including a socket engaging the pivot head.

6. A sash fastener comprising a pair of jointed arms, a mounting pivoted to one of said arms, a leaf spring secured to the other of said arms to extend longitudinally thereof, a headed pivot secured to said leaf spring for movement therewith, and a bracket detachably engageable with said headed pivot, said bracket including a socket designed to embrace the pivot head, and said bracket including a slot extending into said socket of dimensions to slidably engage said pivot.

7. A sash fastener comprising a pair of jointed arms, a mounting pivoted to one of said arms, a leaf spring secured to the other of said arms to extend longitudinally thereof, a headed pivot secured to said leaf spring for movement therewith, and a bracket detachably secured to said headed pivot, said bracket comprising a plate having a recessed socket therein designed to embrace the head of said pivot, and said plate having a slot extending from an edge of said plate to the center of said socket designed to slidably engage said pivot, said leaf spring urging the pivot head resiliently into said socket.

8. A sash fastener comprising a pair of jointed arms, a mounting pivoted to one of said arms, a second mounting pivotally and detachably connected to the other of said arms, and a leaf spring secured to one of said arms and engaging the pivot connecting said jointed arms to create friction at said joint. 70

9. A sash fastener comprising a pair of arms, pivot means connecting said arms, mounting means pivoted to each of the respective arms, and a leaf spring secured to, and extending longitudinally of, one of said arms, said leaf spring engaging said pivot means connecting said arms to create resistance to relative rotation between said arms.

10. A sash fastener comprising a pair of arms, means pivotally connecting said arms, a mounting pivoted to each of said arms, leaf springs secured to, and extending longitudinally of, said arms, said springs urging said arms apart toward the ends of said pivot means, and means limiting the outward movement of said arms on said pivot means.

11. A window fastener comprising a pair of arms, pivot means connecting said arms, mountings pivotally connected to each of said arms, leaf springs extending longitudinally of said arms, said pivot means extending through said springs, spacing means encircling said pivot means between said springs, said springs urging said arms outwardly on said pivot means, and means limiting the outward movement of said arms on said pivot means.

12. A window fastener comprising a pair of arms, means spacing said arms apart, a pivot extending through said arms and said spacing means, a mounting pivoted to one of said arms, a second mounting pivoted to the other of said arms, and an elongated flange projecting from one edge of each arm, the ends of said flanges abutting in one pivotal position thereof to limit relative pivotal movement.

13. A window fastener comprising a pair of jointed arms, a bracket pivotally secured to one of said arms, a leaf spring secured extending longitudinally of the other of said arms, a stile plate, and a pivot extending through said spring for movement therewith, said other arm, and said stile plate, said spring urging said other arm toward said stile plate.

14. A window fastener comprising a pair of jointed arms, a bracket pivotally secured to one of said arms, a leaf spring secured extending longitudinally of the other of said arms, a stile plate, a washer on each side of said stile plate, and a pivot extending through said spring, said other arm, said washers and said stile plate, said spring urging said washers against said stile plate to resist relative rotation therebetween.

15. A window fastener comprising a pair of arms, leaf springs extending longitudinally of said arms, pivot means extending through said springs and said arms to connect the same, said springs urging said arms apart, means limiting the separation of said arms along said pivot means, a mounting, pivot means extending through one of said arms and the associated spring, pivotally connecting said one arm with said mounting, said spring urging said one arm resiliently toward said mounting, a second mounting, a pivot extending through the other of said arms and secured to the associated spring, said last named pivot pivotally connecting said other arm to said second mounting, said last named spring urging said other arm toward said second mounting.

JOSEPH L. QUINN.
